UNITED STATES PATENT OFFICE.

CEASAR A. BORBA, OF SAN FRANCISCO, CALIFORNIA.

STAPLING-MACHINE.

1,369,726.

Specification of Letters Patent. Patented Feb. 22, 1921.

Application filed November 13, 1918. Serial No. 262,376.

To all whom it may concern:

Be it known that I, CEASAR A. BORBA, a citizen of the Republic of Portugal, residing in the city and county of San Francisco, State of California, have invented a certain new and useful Improvement in Stapling-Machines, of which the following is a specification.

My invention relates to improvements in a stapling machine for stapling fabric, such as flags and the like, onto wooden staffs wherein a staple forming means operates in conjunction with a presser foot to press the staple through the fabric and into the staff.

The primary object of my invention is to provide an improved machine adapted to cut and form staples from a continuous wire and press the formed staple through a flag or the like and into a staff.

It is a further object of the invention to provide an improved means whereby the upper surfaces of staffs of different diameters may be held within the same plane so that flags and the like of different sizes may be stapled to staffs of suitable diameter without altering the throw of the mechanism.

It is also an object of the present invention to provide an improved machine of the character described having few and simple parts whereby an efficient machine may be cheaply produced having a maximum efficiency.

I accomplish these and other objects by means of the device disclosed in the drawings forming a part of the present specification wherein like characters of reference are used to designate similar parts throughout the said specification and drawings, and in which—

Figure 1 is a broken front elevation of the machine;

Fig. 2 is a rear elevation;

Fig. 3 is an enlarged detailed view of the wire feeding, cutting and the lower portion of the staple forming means, disclosing the feeding means in operation;

Fig. 4 is a similar view disclosing the cutting means in operation after the free end of the wire has been secured by forming means;

Figs. 5, 6, 7 and 8 are detailed views dis-

closing the successive stages of the staple forming and stapling means;

Fig. 9 is an enlarged detailed view disclosing the manner in which a severed staple length of wire is engaged by the forming means;

Fig. 10 is a similar view disclosing the manner of forming the staple; and

Fig. 11 is a detailed plan view of the cutting mechanism.

Referring to the drawings the numeral 1 is used to designate a suitable frame having a central web 2 therein and a standard 3 at one end of said frame 1 to support a suitable reel 4 containing a substantially continuous wire 6.

The wire 6 is passed through a slidably mounted plate 7 having an aperture 8 therein intercepted by a longitudinal passage 9 through which passes the wire 6.

A latch 11 is pivotally mounted upon the plate 7 and has an offset foot 12 on the bottom thereof which extends inside of the aperture 8 to engage and bind the wire 6 against the bottom of said aperture 8 and the longitudinal passage 9 when moved by a connecting rod 14 pivotally connected to a lever 16 pivotally mounted upon the frame 1 as at 17 and provided at its upper end with an adjustable roller 18 which is engaged in a greater or lesser degree, according to the position of the said roller 18, by means of a suitable cam 19 on a power shaft 21.

As the shaft 21 is rotated by means of a gear 22 meshing with a pinion 23 on a driving shaft 24, the cam 19 operates to engage the roller 18 on the lever 16 and move the upper end of the latch 11 in the direction indicated by the arrow in Fig. 3 of the drawings, which movement will move the foot 12 to engage the wire 6 and bind the same between the lower end of said foot and the bottom surface of the aperture 8 and cause the plate 7 to move forward against the tension of a spring 26 and feed a predetermined staple length of the wire 6 through an aperture or bore 27 adjacent a cutter 28 arranged at an angle to said bore 27. The cutter 28 is pivotally mounted as at 29 and is provided with a slot 31 within which rests an operating arm 32 for the

cutter 28, said arm being mounted upon a shaft 33 connected at the rear of the frame 1 by means of a connecting rod 34 to a lever 36 in turn operated by a cam 37.

5 A plunger 39 is slidably mounted within the central web 2 and at right angles and adjacent to the cutter 28 and is provided with an enlarged portion 41. A spring 42 is interposed between the enlarged portion 10 41 and the back of a bracket 43 supporting a staff holder 44 having a series of arcuate seats 46 of different depths whereby staffs 47 of different diameters may be held with their upper surfaces within the same plane 15 and always at the same distance below the bottom of the staple forming mechanism hereinafter more fully set forth.

The plunger 39 is normally projected into an operative position as indicated in Figs. 20 5 and 6 of the drawings, by means of a lever 51 fulcrumed as at 52 to a bracket 53 mounted upon the back of the central web 2. The upper end of the lever 51 is operated by means of a suitable cam 54 to 25 release the plunger 39 and thereby permit the tension of the spring 42 to remove said plunger 39 from the path of the staple forming mechanism.

The staple forming mechanism consists of 30 a bar 61 vertically and slidably held by a plate 62 on the central web 2. The bar 61 is provided with a slot 63 in the lower end thereof said slot 63 being in turn provided with grooves 64 and a slightly grooved bot- 35 tom 66.

The upper end of the bar 61 is provided with rollers 67 which are engaged by a suitable cam 68, mounted upon the power shaft 21, to operate the bar 61 in a manner here- 40 inafter more fully set forth.

A second bar 69 is slidably mounted back of the plate 62 and is provided with a driver 71 on the lower end thereof which projects into the slot 63 in the bottom of the bar 45 61, said driver being also provided with a groove 72 to assist in holding a formed staple.

A lever 73 is pivotally mounted upon the central web 2 and engages a pin 74 on the 50 bar 69 which pin 74 extends through a slot 76 in the plate 62. A spring 77 normally raises the lever 73 which in turn raises the bar 69 and driver 71 against the upper end of the slot 63 in the bottom of the bar 61 55 which upward pressure normally retains the rollers 67 in engagement with the cams 68.

The holder 44 is arranged directly below the bars 61 and 69 to hold the upper surfaces of staffs 47 of various diameters the 60 same distances below the bottom of the bar 61 and driver 71 of the bar 69.

The cutter 28 is slidably mounted to regulate the length of staple to be cut from the wire 6 and is adjustably held in position by 65 means of a suitable set screw 81.

The length of wire to be fed by means of which the length or size of the staple is to be regulated may be adjusted by moving the roller 18 in the lever 16 to regulate the period of engagement with its respective 70 cam 19.

In operation the cam 19 first operates the lever 16 to actuate the latch 11 and thereby engage and move the wire 6 and slide 7 toward the cutter 28. When the cam 19 releases the roller 18 the spring 26 returns the slide 7 to normal position, the foot 12 of the latch being arranged to release the wire 6 on its return movement.

The cam 37 then operates, through the 80 medium of the lever 36, connecting rod 34 and shaft 33 to operate the arm 32 and the cutter 28 which cuts or severs the free end of the wire 6 at an angle thereto to provide a sharpened end for the staple legs.

85 Simultaneously with the operation of the cam 37 the cam 68 engages the rollers 67 on the top of the bar 61 and moves said bar a slight distance downward until the groove 66 in the bottom thereof engages and impinges the free end of the wire 6 onto the plunger 39.

90 After the free end of the wire 6 is cut or severed the cam 68 further operates to move the ends of the severed wire 6 down onto the side of the plunger 36 and into the grooves 64 in the sides of the slot 63 in the bottom of the bar 61 as disclosed in Fig. 10 of the drawings.

95 A further rotation of the cam 68 moves 100 the bars 61 and 69 downwardly, carrying the formed staple onto a staff 47 held within one of the arcuate seats 46 of the staff holder 44. The groove 66 in the bottom of the bar 61 tends to center the staff 67 with the staple held within the slot 63 of the bar 61. A further rotation of the cam 68 carries a bar 88 against a roller 89 in the top of the bar 69 and moves said bar 69 and driver 71 thereon to drive the staple through the fab- 105 ric and into the staff 47.

Having thus described my invention, what I claim as new and desire to secure by Letters Patent is—

1. A stapling machine for stapling fabric 115 and the like onto wooden staffs, comprising a staff holder having arcuate seats therein of different depths whereby staffs of different diameters may be held with their upper surfaces in the same plane; a staple forming mechanism arranged above the staff holder; means for feeding wire to the staple forming means; and means slidably mounted within the staple forming means for driving a formed staple into the staff.

120 2. A stapling machine comprising a staff holder having arcuate seats thereon of different depths whereby staffs of different diameters may be held with their upper surfaces within the same plane; a staple form- 125 130

ing means arranged above the staff; means for feeding a continuous wire into the staple forming means; means for cutting a staple length of wire from the continuous wire; 5 means for operating the wire forming means to form a staple; a driver slidably mounted within the staple forming means; and means

for operating the staple forming means to carry the staple adjacent the staff and for operating the driver to drive the staple into 10 the staff.

In witness whereof, I hereunto set my signature.

CEASAR A. BORBA.
